UNITED STATES PATENT OFFICE.

CARL SCHWARZ, OF CHARLOTTENBURG, NEAR BERLIN, GERMANY, ASSIGNOR TO WESTINGHOUSE ELECTRIC & MANUFACTURING COMPANY, A CORPORATION OF PENNSYLVANIA.

ARRANGEMENT OF CONNECTIONS FOR SENDING AND RECEIVING ELECTRIC WAVES.

Application filed October 31, 1921, Serial No. 511,831, and in Germany May 26, 1921.

This invention relates to a system for sending and receiving radiosignals, although it is particularly adapted to the use of waves guided by wires, the invention is not limited thereto but also includes space radiosignaling.

It is an object of this invention to provide a means whereby the sending and receiving energy may be divided over a number of paths and it includes arrangements for securing proper balancing among the paths.

It is a further object of this invention to devise a system wherein the balancing just mentioned may be used to prevent energy from the sending apparatus from actuating the receiving apparatus at the same station.

It is a further object of this invention to provide for interchanging the connections of the several paths so that great exactness of balancing shall not be required.

Other objects and details of construction will be apparent from the following description and the accompanying drawing, wherein—

Figure 1 is a diagrammatic illustration of one embodiment of my invention.

Fig. 2 is a similar illustration of another embodiment of my invention, and

Fig. 3 is an illustration of the modification of the form shown in Fig. 2.

In Fig. 1, 1, 2 and 3 represent three antennæ. These may be ordinary radiating antennæ or they may be wires parallel to the line wires shown at 15, 16 and 17. These line wires may be a power-transmission line, the wires of an ordinary telephone line or or the wires of a high-tension transmission line.

To each of the antennæ is connected a tuned circuit including, respectively, the inductors 4, 5 and 6. These inductors are joined together star-fashion and the center is connected to the ground. The outer end of each inductor is connected to its respective antenna. Adjustable condensers 7, 8 and 9, in parallel to each of the inductors, respectively, provide for the tuning.

The sending device indicated by the word Sender is of any desired form. It is not illustrated because the particular form of sending device used is not related to the invention covered by this application. In the same way, the receiving device is indicated by the word Receiver appearing adjacent in-

dicator 12. The sending device delivers its energy to two coils 10 and 11 connected in series and in inductive relation, respectively, to the coils 4 and 5. The receiving device obtains energy through the coil 12 which is inductively related to the coil 6. The coupling between the coils 10 and 4 and the coupling between the coils 11 and 5 are so adjusted that the point 14 becomes a potential node, so that the electrical changes in the coils 4 and 5 do not effect the coil 6. The energy sent out by the sending device, therefore, is delivered to the antennæ 1 and to the wires 15 and 16 without affecting the receiving device. The tuning devices 7 and 8 may, by proper adjustment, be made to accomplish the same result, even when the coupling just described is not properly adjusted. If neither of these adjustments secures a perfect balance, it is possible to further adjust the balancing by altering the electrostatic coupling between the wires 1 and 15 or the wires 2 and 16.

When the balancing of the energy delivered by the sending device is sufficiently perfect so that it does not affect the receiving device at the same station, there will still remain sufficient unbalancing in the line wires 15, 16 and 17 so that a distant station, although its sending device be adjusted for balancing, will deliver unbalanced energy through the antennæ 1 and 2, and the receiving device at the illustrated station will be actuated thereby. The receiving device is also actuated by energy received from the wire 17 through the antenna 3. It will be apparent that, even when the balancing is imperfect, the point 14 can be made to act as a potential node, because it is connected to the ground and is, therefore, kept at zero potential.

In Fig. 2, a similar system is illustrated. At station A, the sending device is represented by S1 and the receiving device by R1. At station B, the sending device is represented by S2 and the receiving device by R2. The lines 15, 16 and 17 are connected to the several inductors 4, 5 and 6 by capacities 18, 19 and 20. These capacities may be pairs of parallel wires as already described in connection with Fig. 1, but preferably they are formed by the insulating supports of the wires 15, 16 and 17; for example, by

connecting to metallic coatings upon opposite sides of the suspension insulators.

The effect of the balancing arrangement in Fig. 2 is, as already described, that the sending device S1 delivers energy so divided between the coils 4 and 5 at station A that the point 14 there remains at constant potential. The coil 6 will be undisturbed thereby and, therefore, the receiver R1 will not obtain current from the sending device S1. The current sent out from the sending device S1 travels over the wires 15 and 16 and reaches the point 14 at station B over the coils 4 and 5 there, from this point it returns to station A over the coils 6 and wire 17, reaching the point 14 at station A. Although this description of the circuit seems to indicate a flow through the coils 6 at each station, the effect of the balancing described above shows that this current is theoretically zero. Adjustment at station A can produce this result at that station so that the energy sent out by the sending device S1 will not affect the receiver R1. There will, however, be sufficient unbalancing in the line so that the receiver R2 at station B will be affected. In the same way, adjustments at station B can be made so that the sending device S2 will not affect the receiver R2 but will produce an effect at the receiver R1.

It will be obvious that this arrangement causes a very small current to flow in the wire 17 and that the energy received at the receiving instruments is small. This disadvantage can be avoided by interchanging the connections, as illustrated in Fig. 3, where the corresponding parts are indicated by the same reference characters. The two inductors 5 are connected at each station as in Fig. 2 but the connection from the inductor 4 at station A, instead of going to the inductor 4 at station B, goes to the inductor 6, and the connection from inductor 6 at station A goes to the inductor 4 at station B. With this arrangement, when a balance is obtained at station A, so that no energy is delivered from the sending device S1 to the receiver R1, a considerable proportion of the energy from the sending device S1 will be received at the receiving device R2, since a direct path from the inductor 5 in station A over wire 16, inductor 5 at station B, inductor 6 at station B and the return wire to the inductor 4 at station A exists, which receives the full potential difference at station A. Proper balancing between the inductors 5 and 6 at station B is, in this form, correlated with the balancing between inductors 4 and 5 at station A. This leaves the balance between inductors 4 and 5 at station B available for the operator there so that he can ensure that the sending device S2 will not affect the receiver R2.

It will be obvious that the principle illustrated in these three embodiments of my in-

vention is capable of many applications. It is also obvious that many variations in the details of construction may be made without departing from the spirit of this invention, I therefore, do not intend the patent to be limited except as necessitated by the prior art or indicated by the claims.

I claim as my invention:

1. In a signaling system, three line wires connecting two stations, a connection at the first of said stations between the first and second of said line wires, means for impressing signaling energy upon said connection, said means being balanced, whereby a potential node will be present in said connection, a connection between said potential node and the third wire, a signal-receiving device in said last named connection, a connection at the second station between the first and third of said wires, means for impressing signaling energy upon said connection, said means being balanced, whereby a potential node will be produced in said connection and a connection between said potential node and the second of said wires, said connection including a signal-receiving device.

2. In a signaling system, three line wires connecting two stations, a connection at the first of said stations between the first and second of said line wires, means for impressing signaling energy upon said connection, said means being balanced, whereby a potential node will be present in said connection, a connection between said potential node and the third wire, a signal-receiving device in said last named connection, a connection at the second station between the first and third of said wires, means for impressing signaling energy upon said connection, said means being balanced, whereby a potential node will be produced in said connection, a connection between said potential node and the second of said wires, said connection including a signal-receiving device, the connection including the signal-receiving device at each station being balanced with both parts of the signal-sending connection at said station, whereby the signal-sending energy at each station is prevented from effecting the receiving device at that station.

3. In a three-wire signaling line, a bridge across two of said wires, a bridge between one of said two wires and the third wire, a connection between said third wire and the neutral point of said first named bridge, a connection between the neutral point of the second named bridge and the remaining one of said two wires, signal-receiving devices in the said connections to the neutral points and means for impressing signal-sending energy upon said bridges.

4. In a signaling system, two stations, a sending device and a receiving device at each station, a line including a plurality of conductors between said stations, means for

establishing a balanced relation at each station whereby the signals sent by the sending device at that station will be without effect on the receiving device at the same station, conductors, whereby the balancing means at one station will not prevent the sending means there from affecting the receiving 10 device at the other station.

5 and one of the conductors being so arranged that signaling frequency energy is attenuated more therein than in certain of the other

In testimony whereof I affix my signature.

CARL SCHWARZ.
